VALVE OPERATING MECHANISM

Robert C. Russell, Dallas, Tex.

Application June 18, 1932, Serial No. 618,004

26 Claims. (Cl. 123—90)

This invention relates to valve operating mechanism or valve lifters for use primarily in connection with internal combustion engines and the like, and more particularly to what may be termed automatically compensating or self adjusting rocker arms constituting a principal part of said mechanism.

In general, this invention seeks to produce a practical form of oscillating valve lifter means or rocker arm, novel and rugged in its construction, subject to minimum wear, quiet and positive in its automatic compensation function, comprising few parts, and which can be produced so economically as to justify its use generally on all types of engines employing rocker arms as a part of the valve actuating mechanism.

An object of this invention is to produce novel self adjusting rocker arms for use in connection with internal combustion engines for actuating the valves thereof in relation to their seats. This rocker arm means, according to my invention, automatically maintains a no-clearance operating relationship or engagement between all connections and parts of the valve operating mechanism interconnected between the engine or machine driven cam and the valve seat in the cylinder, maintaining said no-clearance regardless of operating conditions occasioned by variations in temperature and length of the valve operating parts. This promotes engine speed, performance and efficiency by virtue of improved valve timing which is held constant, avoids harmful impact or hammering and wear between all parts including the valve seats, and therefore eliminates noise and vibration. Such a no-clearance operating engagement for all parts, as afforded by this invention saves frequent manual adjustment and engine repair, and affords softness of valve closing and smoothness in operation for the life of the engine or machine.

The necessity for a solution of the problem involved is pronounced, especially so in present day high speed internal combustion motors which depend on precisely accurate and constantly uniform valve timing for maximum engine efficiency. In aviation engines especially, which employ very substantial valve operating clearances, the solution of the problem is of outstanding importance and attains increased engine power and speed, avoids valve trouble and promotes safety.

A further object is to produce a new form of silent and self adjusting rocker arm of a mechanical type which functions without the necessity of an oil cushion or other liquid supply. Hence the invention is distinguished in this fur-

ther respect from valve operating mechanism and rocker arms of the hydraulic type. However, lubrication, as such, is an aid to smoothness in the operation of my compensating or self adjusting mechanical rocker arms.

An outstanding object of my invention is to produce a rocker arm means which automatically compensates in two directions, i. e., for expansion, contraction and wear of all the valve operating parts with their bearings and connections, from and including the valve seat itself to and including the cam and cam shaft. To attain this end, a main object is to mount the rocker arm on an automatically adjustable or compensating bearing means which is coordinated with means for positively imparting a rotative adjusting movement to said bearing, first in one direction and then the other, whereby the rocker arm automatically relieves itself of either cramped or loose position, by snugly resetting itself to accommodate either a longer or shorter valve stem and/or push rod or other parts as they vary in length during operation.

The invention comprehends the use of a positively driven mechanical means for transmitting an adjusting or freeing movement from any convenient source of motion to the compensating bearing to actuate it in one direction to definitely ease or free it and the rocker arm from cramping or undue tightness, together with a torque spring for urging said bearing in the other direction to reset it and the rocker arm to their normal no-clearance engagement with and in relation to all other elements of the operating combination, and finally a locking or clamping means which positively grips and fixes the bearing and its rocker arm together against relative motion so they oscillate as a unit when actuating the valve from its seat, these stated operations being precisely timed to start and finish their full cycle while the valve is on its seat and the rocker arm is idle. My invention comprehends a simple construction of practically no more parts than conventional rocker arms now in use for executing the foregoing complete compensating cycle by effecting all three functions to-wit, freeing, resetting, and locking, during the period the heel of the engine cam is idly traversing the operating means.

Pursuant to the foregoing, it is an object and point of novelty in this inventive concept to produce a self adjusting rocker arm mechanism comprising a plurality, more particularly a pair, of interconnected rocker arms, whereof each arm adjusts the other in alternation, to continuously

take out the lost motion or play as the latter develops, whether from wear of parts or variation in temperature with the consequent accompanying variation in operating length condition of push rods or valve stems. In this connection, the example of the invention illustrated herewith shows a pair of engine valves and their coacting rocker arms. An operating connection is provided between the two arms, whereby one rocker arm, when opening and closing its valve, automatically initiates the self adjusting function of the other rocker arm so the latter may automatically compensate and set itself to a no-clearance relationship with its particular valve parts while its valve is on its seat and thus condition itself for actuating its valve in relation to its seat. Inasmuch as rocker arms are usually provided in closely arranged pairs on each cylinder head of an engine to actuate the intake and exhaust valve of that cylinder, I transmit the working motion of one rocker arm to the other rocker arm when the latter is idle by which to initiate the resetting of the latter to its no-clearance position, but the invention comprehends deriving this working motion from any other convenient source of motion. The cam shaft affords this ready source of mechanical movement and so it is found practical and more direct in most engines to take this movement, required at a given rocker arm bearing, from the adjacent oscillating rocker arm itself, but the required motion may be derived from a special cam on the cam shaft or from other driven means. I mention these considerations inasmuch as I illustrate my invention with what is regarded as the simpler and hence better form of construction. In this connection, it is a further object to produce in combination a self adjusting rocker arm pair for actuating the exhaust and intake valve pair in the same cylinder. The rocker arm pair (intake and exhaust) of any given cylinder, in a multi-cylinder engine, is conveniently adapted to my invention since one of the valves is always at rest on its seat and hence its rocker arm is idle so that the active valve and rocker arm are available to adjust the idle rocker arm.

With the foregoing objects and others in view, reference is now made to the accompanying drawings showing one of the concrete examples of the invention in which certain changes in structure and mode of operation may be resorted to without departing from the principle of the invention. Figure 1 shows a side view of one of the compensating rocker arms of a coordinated exhaust and intake valve pair in one cylinder. Said arm is merely one of the parts in the chain of operating connections interposed between a conventional valve in a fragmentary portion of a cylinder head and the cam shaft of an engine. All parts are shown in rest position with the valve on its seat and the rocker arm has completed its cycle of adjustment and attained its normal no-clearance working position ready to open the poppet valve at the next revolution of the cam. This view may also be considered as partially developed on the section line 1-1 of Figure 2, except that the sectioned rocker arm of Figure 2 is assumed to be complete when laying out this side view of Figure 1, and also the section line 1-1 is assumed to pass thru the torque spring.

Figure 2 is a fragmentary plan view of the self adjusting rocker arm means or pair, and one of the rocker arms is shown in section, as cut along the section line 2-2 of Figure 1.

Figure 3 is a plan view of a torque spring means interconnected between the two dependently operating self adjusting rocker arm bearings. This spring urges first one bearing with its arm and then the other to the desired no-clearance operating position.

Figure 4 is a detailed view developed on the section 4-4 of Figure 3, showing one end or coil of the torque spring wrapped around the eccentric-type compensating bearing on which the rocker arm is carried, and the arrow shows the direction of the applied torque as exerted by the spring. This view also shows diametrically opposed clearance gaps or lost motion spaces left between the operating connections of the rocker arm pair by which to transmit only a necessarily slight self adjusting action from one rocker arm to the self adjusting bearing of the other arm and by which to accommodate the self adjusting apparatus to the differential variation between an exhaust and intake valve.

Figure 5 is a rear view of the uppermost portion of the mechanism in Figures 1 and 2 and shows the upper ends of the two push rods of the valve operating pair as connected with their respective rocker arms.

Figure 6 shows a cluster view of the separate parts placed in aligned order of assembly and constituting the few elements forming the operatively connected self adjusting rocker arm pair.

Figure 7 shows a side view of the rocker arm per se removed from its self adjusting bearing and showing a slot in the hub thereof disposed on the far side away from the engine cam shaft and by which the rocker arm hub is rendered contractible and expansible to lock or clamp its bearing therein which is a feature of this invention.

Figure 8 shows a longitudinal section thru the axis of one of the compensating bearings for one of the self adjusting rocker arms of the coordinated pair and having a motion transmitting sleeve to impart an easing movement to the adjacent bearing for the other rocker arm.

In the drawings, a typical valve in the head engine is indicated diagrammatically by reference 120 to a fragmentary portion thereof, say a cylinder head 3 having valve seats 4 and 5 defining intake and exhaust port openings leading to the cylinder of said engine 3. A pair of poppet valves of the usual kind include valve heads 6 and 7 with stems 8 and 9, respectively. Valve closing springs 10 and 11 load the valve stems 8 and 9 in the usual way for returning and maintaining the valves 6 and 7 on their seats, following the opening operation thereof thru the agency of a rocker arm individual to each valve stem 8 and 9 which is actuated by a conventional cam also individual to each rocker arm.

A pair of rocker arms 14 and 15 are mounted on a common rocker arm shaft 16 supported by 125 brackets 17 or other suitable means above the cylinder block or engine head 3. A cap screw 18 for each bracket or post 17 securely fixes the rocker arm shaft 16 in the several brackets 17 along the top of the cylinder block 3 and also anchors said brackets to the cylinder block. This arrangement mounts the rocker arm shaft 16 against rotation and adapts it for the support of the self adjusting valve operating rocker arm means.

A pair of push rods 21 and 22 are actuated by a common cam shaft having a cam, including the usual lobe 23 and cam heel or drop 24, for each push rod and related valve 8 and 9, respectively, this mechanism operating in a conventional man-

ner and individual to each valve 6 and 7, as will be understood. An ordinary tappet or valve lifter 20 constitutes the cam follower which rides the cam 23, 24 to actuate the rocker arm and open its valve when the cam lobe traverses the follower 20. Each upper end of the pair of push rods 21 and 22 is operatively connected in any approved manner with the end portion or rear arms 25 and 26 of each rocker arm 14 and 15, as for example, by a ball and socket joint 27 including an adjusting screw and lock nut means 28 used for adjusting these operating connections when assembling the mechanism.

The ball joint 27 effectively transfers the thrust of the cam lobe 23 and its respective push rod to the oscillating rocker arm. The use of the screw adjustment 28 for accurately setting the ball and socket joint 27 is optional and merely a convenience and need be adjusted only once, as for example, when the engine is first assembled, whereupon the self adjusting rocker arm pair 14 and 15 thereafter will maintain a constant no-clearance thrust connection or engagement in the ball and socket joint 27. If desired, the screw adjustment means 28 may be omitted since the compensating means for each rocker arm can be manufactured on a precision basis and within limits as to dimensions of parts by which, after assembly, the functioning of the invention, upon the first revolution of the engine, will automatically adjust and inherently set up the desired operating no-clearance working pressure or engagement throughout the general combination of all parts, including the push rod connection 27, the rocker arm contact at the valve stems 8 and 9, and between the cam and follower 20.

As will be understood by those conversant with the art, I have for convenience illustrated the valve pair 6 and 7, as an intake and exhaust, in the cylinder 3. Hence the reader will bear in mind that one valve of the pair is usually on its seat and thus its rocker arm is at rest and in a receptive state to automatically reset itself to the operating length condition of all parts at the instant of adjustment when the other valve is off its seat and, therefore, when the rocker arm of the open valve is in motion and at work. The invention contemplates using the motion of the working or active rocker arm to initiate the resetting or self adjusting action of the idle rocker arm which is not working. This function rapidly switches from one rocker arm to the other, back and forth, in constantly recurring function, while the engine is running, and the action is characterized by a minimum of relative movement between the parts which avoids wear and leads to long life. The two valves, intake and exhaust, with the related rocker arms of the same cylinder 3, do not necessarily have to themselves be interconnected but that arrangement is most convenient. Any two adjacent valves, where one is closed when the other is open, may be selected for this interconnected mode of operation.

The foregoing explanation outlines in a general way a typical form of internal combustion motor of a type employing a rocker arm, as a part of the valve operating connections or mechanism, for each valve and hence a rocker arm pair of each cylinder. Based upon the foregoing example of conventional engine valve means, a description will now be given of the features of construction and mode of operation constituting this invention and by which all the advantages of self adjustment and sustained no-clear-

ance operating relations are effectively carried out.

The first rocker arm 14 is provided with a hub 30 and similarly the second rocker arm 15 is provided with its hub 31. The two rocker arms may be the same in form and the inside bore thereof is designed as a bearing surface within which an eccentric undergoes perceptible rotative adjustment in both directions, up and down, as indicated by the two arrows U and D in Figure 1, when the valve is on its seat and the rocker arm is idle. The hub 30 is slotted longitudinally at 32, and the other hub 31 is similarly slotted at 33. The rocker arm slots 32 and 33 remove sufficient metal or stock from the hubs as to produce a definite contractile slotted opening to afford a degree of flexibility by which each hub bearing 30 and 31 may contract and expand to a perceptible degree, thereby slightly varying its inside diameter. The hub slots 32 and 33 are cut thru or otherwise formed longitudinally thru the hub portion above the rocker arm shaft 16, and hence the axis of the rocker arms is disposed generally between said slots and the engine cam shaft means 23. Therefore, the upward thrust of the cam 23 and related push rod 21 against the arm 25 tends to close the slot 32 which contracts the inside diameter of the hub bearing since the spring loaded valve stems 8 and 9 initially resists pivotal action of the rocker arm as a whole, and the result is a definite closing and pinching or gripping tendency at each hub slot 32 and 33.

Each rocker arm hub 30 and 31 is mounted on the rock shaft 16 thru the agency of an eccentric self adjusting bearing means having a novel mode of operation and which moves in both directions to compensate for contraction and expansion of the entire valve operating combination. There is provided an eccentric 35 for and with in the rocker arm hub 30 and a similar eccentric 36 in the other rocker arm hub 31. The inside axial bore 34 of each eccentric 35 and 36 constitutes its working bearing on which said eccentrics and the rocker arms carried thereby oscillate clockwise on the journal or shaft 16, as in Figure 1, to open their respective valves 6 and 7 in the usual way, and oscillate anti-clockwise to afford a valve closing motion by expansion of the springs 10 and 11. The outer face 29 of each eccentric 35 and 36 also constitutes a bearing surface which undergoes a limited rotative adjusting movement in both directions, as at U and D in Figure 1, within each rocker arm hub 30 and 31 each time the valve is on its seat.

The outside diameter 29 of each eccentric 35 and 36 is slightly less than the inside diameter of the hub bearings 30 and 31 when the latter are relaxed and at their greatest diameter which condition exists during the period the valve is on its seat and hence while the cam heel 24 is idly traversing the cam follower 20. In other words, each eccentric has a free bearing fit with in its rocker arm hub and is rotatably free to turn therein when said hub is at rest and relaxed normally at its greatest diameter. However, the fineness and accuracy of the rotating bearing fit of each eccentric 35 and 36 within their respective hubs 30 and 31 is such that the eccentric is pinched, locked or clamped within the hub and moves rigidly as a unit therewith upon the slightest contraction of said hub as afforded by the slot pinching means 32 or 33 when the cam lobe 23 and push rod 21 or 22 thrust

upwardly against one end of the rocker arm 14 or 15.

The first eccentric 35 is made with an extension bearing sleeve or reach hub 37, and the second eccentric 36 is similarly made with a like extension sleeve 38. The two sleeve means 37 and 38 reach or bridge the space between the two dependently self adjusting rocker arms 14 and 15 and coact with each other by imparting an oscillating movement back and forth, one to the other. The eccentrics with their integral sleeve extension means 37 and 38 have a common axis for their internal bores 34 and for bearing fit rotatable upon the stationary rocker arm shaft 16, particularly in constructions where the rocker arms 14 and 15 are somewhat distant from each other.

The sleeve or bearing extension 37 is notched or stepped back from its end by cutting away a portion thereof circumferentially between the eccentric bearing body 35 and said outer end. The cutaway portion in effect leaves a notched end having oppositely disposed companion shoulder edges or jaws 39 and 40 which may be parallel to the shaft 16 and turn or rock circumferentially thereon. In the same way the self adjusting bearing 36 has the outer end of its sleeve 38 designed to form a pair of oppositely spaced shoulder means 41 and 42. The two notched sleeves 37 and 38 are loosely engaged or clutched together on the shaft 16 by which a portion of the rotative movement of each sleeve is communicated back and forth to each other in constantly recurring function.

The integral shoulder pair 39 and 40 measure slightly less than a semi-circle, ordinarily a few thousandths of an inch, than one hundred eighty degrees; and the same is true of the spaced integral shoulders 41 and 42. Hence the jaw 39, 41 and companion jaw 40, 42 may only close one at a time or coact in alternation, one after the other. As the sleeve jaw 39, 41 closes, the opposite jaw 40, 42 opens and vice versa. One sleeve, say 37, therefore, has a pronounced motion relatively to the other, say 38, before engaging and actuating the latter, and reversely as to sleeve 38 the same is true in relation to the former.

The separate shoulders 40 and 42 coact to transmit motion from the eccentric bearing 35 to 36 when rocker arm 14 tilts clockwise (Figures 1 and 4) to actuate its valve 6; and similarly the other set of shoulders 39 and 41 coact by which the eccentric 36 reversely acts on 35 to oscillate the latter when the other rocker arm 15 tilts to open its valve 7. Both actions kick up, as at U in Figure 1, on the compensating bearings 35 and 36 to bodily lift the rocker arms 14 and 15 to ease and free them of and from working pressure or mechanical cramps, so to speak, by taking out the no-clearance engagement at the ends of the valve stems 8 and 9 to insure that each valve 6 and 7 positively seats.

When the two eccentrics 35 and 36 are assembled on the shaft 16, there is left the predetermined clearance or lost motion space between the adjacent coacting shoulders forming each operating jaw pair 39, 41 and 40, 42, as heretofore mentioned. This clearance permits of a limited oscillation of either eccentric 35 or 36 in relation to the other before one eccentric actually coacts with and kicks up or trips the other to initiate the automatic upward adjustment of the latter. In this way, the active or working eccentric and its rocker arm has its valve well open before communicating its bodily lifting adjustment action, as

at the reference U, to the other eccentric and its arm, and thus is avoided undue or over adjustment or lifting of the idle rocker arm. A limited and indeed only a perceptible lifting or easing up and freeing movement of each eccentric is required, to eliminate the mechanical pressure or cramps, so to speak, at 27 and at all other points of engagement beginning at the cam and extending to the valve seat, and by which to insure perfect and positive closing of the valves 6 and 7 by their springs 10 and 11.

In assembling the mechanism, the eccentric 35 is operatively confined within its cooperating rocker arm hub 30 and likewise for the eccentric 36 and its hub 31. The two rocker arms 14 and 15 are now spaced apart and set to engage the tail or outer end of their respective valve stems 8 and 9. The two reach sleeves 37 and 38 are now disposed in overlapping operative engagement, and the shoulders 39 and 40 of the eccentric 35 are clutched and interconnected in working relation with the shoulders 41 and 42 of the other eccentric 36, as heretofore explained. It is now apparent that the few thousandths of an inch narrow clearance or lost motion space between the adjacent shoulders 39 and 41 and the diametrically opposite shoulders 40 and 42 permit a limited amount of relative motion between the two rocker arms 14 and 15, the same as heretofore explained for the self adjusting bearings 35 and 36. The two-way adjusting eccentric bearings 35 and 36, and hence the rocker arms 14 and 15, are now operatively connected so that the latter portion of the travel of one arm 14 lifts the other perceptibly and vice versa. In view of the slight lost motion or rocking play relatively between the two rocker arms 14 and 15, it follows that each arm attains a rocking start, initially, before kicking up or lifting the other. To emphasize this feature, note again that this space of a few thousandths of an inch is preferably left so that only a portion of the valve lifting oscillation of one rocker arm, say 14, is imparted to the compensating bearing 36 of the other rocker arm 15 when the latter is idle.

The coacting adjacent shoulders 39 and 41 constitute in effect one operating jaw while the other adjacent shoulders 40 and 42 provide an oppositely disposed operating jaw. By varying the jaw space between these coacting adjacent shoulders, it follows that the jaw 39, 41 or 40, 42 open and close sooner or later, as the case may be, in relation to the pivotal action of the two rocker arms 14 and 15. It is found in some engines that the full throw normally required of one rocker arm to fully open its poppet valve is not by any means required to ease and adjustably lift the other rocker arm away from its no-clearance operating relation to permit of a subsequent return to a readjusted and more precisely compensated no-clearance relation to the then changed operating length condition of all the parts in the combination. Consequently, the jaws 39, 41 and 40, 42 are made with the lost motion space so that the shoulder 40 does not pick up and trip its companion shoulder 42 until the rocker arm 14 has spent part of its valve opening movement. Thus is minimized undue movement of the compensating parts in the rocker arm pair.

It is important to note that each compensating element 35 and 36 is mounted on the rocker arm shaft 16 with the major axis of the eccentric disposed horizontally or substantially perpendicular to the axis of the push rods and valve 150

stems. This relation is shown in Figure 1. Therefore, a slight upward (as at U) or clockwise rotative movement of the eccentric 35 very definitely lifts the rocker arm 14 bodily upwardly 5 away from its cooperating push rod 21 and valve stem 8 and insures positive valve seating by relieving or easing the rocker arms of cramped position should the push rod or valve stem have elongated. Likewise the reverse is true when the eccentric 35 is reversely urged rotatively downward (as at D) or counter clockwise, by means to be explained, because the rocker arm 14 is then set snugly downwardly against the top 10 end of the valve stem 8 and the ball joint 27 and thus tightened up to a no-clearance relation. Both rotative adjustments, at U and D Figure 1, start and finish while the valve is on its seat and repeat this freeing and resetting action each time said valve seats.

20 A torque spring has its center 44 anchored in any suitable manner to a stationary support such as an adjustable screw 45 which is adapted to screw up or down in the engine or cylinder head 3 to vary the tension exerted by said spring. A 25 post 46 may be used if desired to support a clip or hook 47 to retain the spring in place while allowing its free ends or coils 48 and 50 to independently exert a downward torque in the direction of the arrow D on both eccentric bearing 30 means 35 and 36 for the automatic tightening up compensating cycle of self adjustment for each rocker arm 14 and 15. The spring 44 has one end 48 coiled about the sleeve 37 and said end is inserted in a spring socket or hole 49 made within 35 the end of the thick body portion of the eccentric 35. The other end 50 of the spring is coiled about the extension jaw 38 and is inserted in a hole 51 similarly made in the other eccentric 36.

The two coils 48 and 50 of the torque spring 43 disposed axially of the bearings 35 and 36 are suitably tensioned to continuously exert a downwardly unwinding or rotative adjusting force by turning both eccentric bearings in an anti-clockwise direction, as viewed in Figure 1. Also the 45 two spring ends react outwardly away from each other and tend to spread outwardly, i. e., they exert a separating force against the two related bearings 35 and 36 to hold the latter toward or in working engagement against the brackets 17 which maintains the rocker arms 14 and 15 in 50 properly spaced position. The adjusting function of both spring ends 48 and 50 is to independently urge downwardly on the two eccentrics 35 and 36, first one then the other, in the direction 55 of the arrow D, thus urging bodily downwardly on both rocker arms 14 and 15 to maintain both ends thereof in no-clearance relation with their respective valve stem and push rod. This constantly recurring downwardly adjusting action, 60 as at D, of the spring takes place of course immediately after the completion of the up-turn of the eccentric, as indicated at U.

In the operation of the valve mechanism of an 65 internal combustion engine, it is well understood how variation in temperature and also wear and impact of parts is accompanied by variation in length of parts. For example, the push rods, the valve stems and the cylinders of an engine expand perceptibly when the engine warms up to 70 running condition. Likewise these parts contract or shorten because of a drop in temperature or due to the fact that wear occurs at the valve seats or other engaging surfaces. The 75 compensating rocker arm means of this invention accommodates all variations in operating length

conditions by automatically taking up for all wear or shortening of parts, and by giving, yielding, or letting out so to speak, when the push rod, valve stem and other parts expand or grow longer. In other words, the eccentric bearing means 35 and 36 cooperate with their respective rocker arms 14 and 15 by moving said arms up and down perceptibly to maintain an easy, yet positive no-clearance operating relation between the engaging surfaces of the rocker arm and valve stem, as well as the ball and socket joint 27, likewise with the cam and valve tappet, and such other parts as are employed in the valve operating mechanism or connections in general.

To describe the complete operation of the invention in one connected cycle, it is now assumed that the engine is running and the cam lobe 23 is idling along the tappet 20. Hence the first rocker arm 14 is standing still and its bearing 35 is assumed to have completed its two stage adjustment comprising the freeing and resetting operations. At this stage the other valve 7 is at rest on its seat 5 and hence its rocker arm 15 is likewise at rest and the eccentric bearing 36 of the latter has just been unclamped in its hub 31 due 100 to the return of said rocker arm 15 to rest position with the heel 24 of the cam idling over the tappet 20, and the rocker arm 15 may be cramped or otherwise slightly off its desired no-clearance relation with other parts. Now as the cam lobe 105 23 approaches the first push rod 21 to thrust upwardly on the first rocker arm 14, the initial lifting impulse is of course resisted by the valve closing spring 10, the result of which is to tension the rocker arm end 25 upwardly which draws and 110 tensions the lower portion of the rocker arm hub 30, thereby contracting said hub 30 and gripping or clamping therein the adjusted bearing 35 since the slot 32 promotes this hub contraction. Thus the previously adjusted eccentric bearing 35 is 115 now locked within the hub 30, is rigid in and turns as a unit with the rocker arm 14, and the latter therefore oscillates clockwise about the axis of the shaft 16, not on or relatively to its self adjusted member 35 while opening its valve 6. In 120 fact, the rocker arm 14 and its eccentric 35 are now definitely locked together and act as a unit to tilt both clockwise and counter clockwise throughout the entire period the cam lobe 23 is traversing and reciprocating the tappet 20 and 125 push rod means 21. In other words, as long as the valve 6 is off its seat, the hub 30 grips and locks the eccentric 35 therein because both ends of the rocker arm 15 are tensioned upwardly and the hub slot 32 is under this combined closing 130 force. The rocker arm hubs automatically lock their respective bearings therein to oscillate said bearings with said hubs against the yielding resistance of the torque spring means 44 tending to hold said bearings in downwardly limited position. 135

The foregoing clockwise tilting action of the rocker arm 14 to open its valve 6 also acts positively (thru the jaw 40, 42) to kick the free or loose eccentric bearing 36 of the other rocker arm 15 upwardly in the direction of the arrow U in 140 Figure 1 and against the torque of the spring end 50 always exerted downwardly on said bearing 36, as indicated by the other arrow D. Hence the torque spring end 50 is wound up or slightly tensioned additionally to its inherent torque by each 145 working stroke valve opening action of the other rocker arm 14 when the latter is actuated by its cam lobe.

Now it is seen that the idle rocker arm 15 has been perceptibly and forcibly lifted or eased away 150

from its push rod 22 and valve stem 9 at each working operation of the other arm 14. As soon as the first working arm 14 and its locked bearing 35 have completed their rocking movement and 5 tilt back to idle position, it follows that the shoulder 40 of the working eccentric 35 draws away from the shoulder 42 of the lifted eccentric 36, whereupon the torque spring end 50 is perfectly free to return the lifted idle eccentric 36 and its 10 rocker arm 15 back downwardly to reset both of its ends snugly up against the push rod 22 and valve stem 9, which action occurs while the valve 7 is on its seat 5 and the cam heel is traversing its tappet. The torque spring coil 50 now definitely completes this resetting function before 15 the cam lobe 23 begins to lift the push rod 22. Any variation in length of the push rod 22 or valve stem 9, which would prevent the valve 7 from seating or which would leave clearance in 20 any moving part between cam and valve seat, is instantly compensated for between the time the eccentric 36 is urged up as at U by the positive mechanical action of the jaw means and returned downwardly to reset it as at D by the resilient 25 action of the torque spring.

There now exists no possible looseness between the idle rocker arm 15 and its push rod 22 or valve stem 9 because the force of the torque spring 44, 50 is sufficient to enforce a firm seating contact 30 in the ball joint 27 and also between the rocker arm and top end of the valve stem. Of course the torque spring is not sufficiently strong to unduly bear the cam follower 20 against the cam heel 23 or force down on the valve springs 10 or 11. 35 The force of each torque spring coil 48 or 50 is just sufficient to instantly set their respective rocker arms snugly down with no-clearance engagement against the respective push rods and valve stems. Also each coiled section of the 40 torque spring 44 easily yields and tends to coil or wind up a little more under the superior mechanically rotated force of the other rocker arm, but the spring is initially installed with applied unwinding torque so as to possess sufficient strength 45 to maintain the rocker arm bodily downwardly at all times except when positively lifted by the sleeve jaw of the opposite rocker arm.

It is now understood that the second rocker arm 15, which was first eased and secondly reset 50 while idle and while its cam heel was traversing the tappet, is now ready to be acted upon by the engine driven lobe of the cam. As said cam lobe begins to ride the tappet and push rod 22, the hub 31 of the rocker arm 15 first grips the automatically compensated and reset eccentric bearing 36 and pinches it so to speak in 55 said hub 31, as hereinbefore explained for the first hub 30 and its self adjusted bearing 35. The rocker arm 15 is now instantly conditioned to rock about its axis 16 because of the pinch slot 33, and there is no possibility of said rocker arm 15 turning relatively on the face 29 of the eccentric bearing 36. Hence the rocker arm 15 now functions in the usual way to open its valve under the throw or thrust of the cam lobe, but characterized of 60 course by the fact that there is no operating clearance between any parts. Quiet operation, therefore, follows and all impact is eliminated due to a complete absence of all operating clearance heretofore ordinarily left in the rocker arms of engines to insure the seating of the valves.

As said second rocker arm 15 tilts on the rock shaft 16 it follows that its bearing 36 anchored therein by the pinch slot 33 now acts reversely back thru its shoulder 42 to pick up the idle

shoulder 40, whereupon this means 40, 42 in jaw closing fashion kicks up the first bearing 35 and its rocker arm 14. Thus I have traced the oscillating action of the twin parts constituting this self adjusting rocker arm pair and the reader will understand that the mode of operation continues in constantly recurring fashion, back and forth, more rapidly than the eye can follow, with the completion of the three stages or cycles of adjustment, ease or freeing, resetting to snug no-clearance, and finally relocking of the bearing in the rocker arm so as to positively avoid adjustment during the valve opening and closing period.

It is important to note that the locking or clamping of the adjusted bearing is effected while the torque spring is holding down on said bearing. Therefore each rocker arm starts its movement with its bearing snugly set to negative all looseness thruout all parts of the mechanism. As the rocker arm continues its oscillating movement and for the duration thereof, the hub pinching slot is responsive to the pressure generated at the cam and at the valve spring. The hub, therefore, positively clamps its bearing so there is absolutely no possibility of the bearing slipping 100 or changing its position in the least way during the rocker arm working period.

The pinch slot at 32 or 33 illustrates an example of bearing clamp means by which said compensating element 35 or 36 is restrained from 105 slipping motion or displacement during the period the rocker arm is under working stress to actuate its valve. This construction affords a frictional gripping and non-slipping engagement throughout the entire circumference of both the hub and 110 bearing and thus positively insures against loss of the no-clearance adjustment which is automatically and so effectively set up throughout all parts of the mechanism just prior to the operating cycle when said rocker arm goes under working stress. It will be appreciated that this pinch hub construction 30, 32 is simple and inexpensive to manufacture, possesses the mechanical leverage advantages over the bearing, as explained, and is preferred in many instances over other forms 115 considered. To grip only a portion of the circumferential surface of the eccentric bearing 35 or 36 does not afford the full measure of frictional holding effort to restrain the bearing against displacement, as accomplished in the concrete embodiment of the invention as here presented. Also it is noted that the hub 30 or 31 is, inherently, its own releasing means, to instantly relax and free its bearing 35 or 36 from its rigidly locked state when the ends of the rocker arm are not 120 under thrust. It is contemplated, however, that other forms of locking and releasable restraining means for the control of the bearing within the hub may be used without departing from the spirit and principle of the invention.

Reference is again made to the function of the self adjusting control, or the loosening cycle thereof, exercised by the motion transmitting jaw means 39, 41 and 40, 42. Should the valve stem 8, for example, be regarded as the exhaust 140 valve, it follows that its expansion may be more rapid and ultimately some two or three thousandths of an inch longer than its companion valve, the intake 7, 9. That being true, this explains that the shoulder 40 does not reach to 145 interfere with the normal adjusting action of the adjacent shoulder 42. The considerable space initially provided at each jaw 39, 41 and 40, 42 adequately accommodates all possible differen-

tial ranges in rate of valve stem variation (contraction or elongation) which may occur. The intake valve stem elongation may lag as the engine warms up, i. e., the intake valve stem ordinarily does not get as hot as the exhaust valve stem and consequently it may be slower in growth and never reach the extreme change as characterizes the more severely treated exhaust valve. The jaw space between shoulders 10 and 40 and 42, or reversely, between 39 and 41, takes care of this variable factor as regards the slight difference in rate of contraction and expansion of the parts. One motion transmitting jaw may ultimately attain a closer working relation than the other as the engine warms up. These provisions, therefore, effectively accommodate the slight variation in operating characteristics, as between an exhaust and intake valve, where they are taken as a pair and made to conform to the operating refinements of my zero or no-clearance rocker arm means.

It will be apparent that the intermittently operated valve pair and its rocker arm group may or may not be in the same engine cylinder, but where the cylinders are in line, there is ordinarily provided a common axis 16 or rock shaft for all rocker arms and the construction and adaptation of my invention is simplified inasmuch as I am able to employ the same axis 16 as an aid in transmitting the desired easing or freeing-up motion from one rocker arm to the compensation means of the other, and vice versa. There are less common engine constructions not having one and the same journal or retaining axis, as at 16, for the rocker arm pair, as for example, in cases where the valves are disposed at an angle to each other in the cylinder, and also where the oscillating axis of each rocker arm hub is angularly related to each other. In such cases, the necessary easing motion for slightly tilting and freeing the respective bearings, is suitably transmitted directly from the cam shaft or other driven means, or may be transmitted from one rocker arm to the other over the angular path therebetween.

I have produced improvements in the rocker arm per se which includes the hub 30 or 31, enlarged over conventional practice if need be, together with the pinch slot 32 or 33 and made of hard metal or otherwise possesses elastic or resilient characteristics by which said hub returns to its normal maximum diameter when relieved of stress; and also, I have produced the new bearing and jawed sleeve means per se represented at 35, 37 or 36, 38. So also my invention resides in the combination of said new rocker arm and the bearing element operative therein. Further, my invention comprehends the interrelated valve and rocker arm pair, in combination. Likewise I have produced, as a new article of manufacture for this particular purpose, the novel one-piece spring means having the two torque coils 48 and 50 which independently react from a common stationary center to reverse or return the compensating bearing to down or no-clearance position, and this construction, in many instances, possesses certain advantages over two separate torque springs.

As a whole, the operating parts of my invention are small and compactly arranged in the space available on standard engines employing rocker arms for actuating the valves. The invention fills a need felt for an economical valve control which is silent, self adjusting, and eliminates wear and deterioration of the mechanism.

What is claimed is:

1. In combination, a valve having a seat and a spring to seat the valve, a cam shaft and oscillating member to actuate the valve in relation to its seat, compensating bearing means on which the oscillating member is operatively mounted, mechanically driven means cooperating with the compensating bearing means to positively shift same in one direction after the valve has reached its seat to free the entire combination of cramping action whereby said valve is positively seated by its spring, resilient means operable independently of the mechanically driven means to urge the compensating bearing means in the other direction while the valve is still on its seat to snugly set up the cam shaft and oscillating member into a no-clearance operating engagement, and locking means to positively fix the compensating bearing means and oscillating member rigidly together to operate as a unit while the valve is still on its seat.

2. Valve operating mechanism for engines and the like comprising a rocker arm having a bearing hub adapted to oscillate about a retaining axis, a compensating bearing mounted for free movement within the hub and on the axis, releasable clamping means cooperating with the rocker arm hub and the bearing to positively lock said bearing when said rocker arm is in motion so they move together as a unit and also releasable when the rocker arm is at rest to afford freedom of movement of the bearing within the rocker arm at that time, mechanically driven means connected with the bearing to turn it in one direction when the clamping means is released, and resilient means to reverse the bearing and turn it in the other direction while the rocker arm is still at rest.

3. Valve operating mechanism for engines and the like comprising a rocker arm having a hub, a compensating bearing rotatably confined in the hub, releasable clamping means cooperating with the rocker arm hub and the bearing therein and operative when said rocker arm is in motion to positively lock them together as a unit and releasable when the rocker arm is at rest to afford freedom of movement of the bearing within the rocker arm, mechanically driven means oscillatory on the axis of the rocker arm and connected with the bearing to turn the latter in one direction when the clamping means aforesaid is released, and a torque spring having one end connected to the bearing and the other end held stationary to reverse the bearing and turn it in the other direction while the rocker arm is still at rest.

4. Valve operating mechanism comprising a rocker arm adapted to oscillate on a rock shaft and to actuate a valve in relation to its seat, a hub of greater diameter than the shaft and provided with means to afford contraction and expansion of said hub when the latter is in motion, an eccentric confined in the hub and bored to form a bearing on the rock shaft, said eccentric having its major axis disposed perpendicular to the valve, an actuating device to adjust the eccentric upwardly away from the valve when the rocker arm is not in motion, and a torque spring connected with the eccentric to adjust it downwardly also when the rocker arm is not in motion.

5. A rocker arm for actuating spring loaded valves and having a bearing hub provided with a longitudinal slot therein to afford hub contraction, an eccentric in the bearing hub free to rotate

- therein but subject to a clamping action to lock it for oscillation with the rocker arm when the latter contracts, and means to adjust the eccentric in the hub and thereby reset the rocker arm 5 to a no-clearance engagement with the valve.
6. A rocker arm for actuating spring loaded valves comprising a bearing hub formed in said rocker arm, said hub being cut thru to its bearing to render the latter variable in diameter, an 10 eccentric rotatably free within the bearing hub when the latter is at its greater diameter and gripped therein against rotation when the hub diameter reduces, and means to adjustably turn the eccentric first in one direction and then the 15 other to adjust the rocker arm to a no-clearance relation with the mechanism.
7. A rocker arm for actuating a spring loaded valve, comprising a bearing hub provided with a longitudinal slot therein formed above its axis of 20 oscillation and on the side of said axis opposite that of the valve, an eccentric in the bearing hub free to rotate therein but subject to a clamping action to lock it for oscillation with the rocker arm when the latter actuates the spring loaded 25 valve causing said hub to contract, and means to adjustably turn the eccentric in the bearing hub and thereby set the rocker arm to a no-clearance operating relation with the valve.
8. A rocker arm for actuating a spring loaded 30 valve and adapted to be actuated from a cam shaft, comprising a bearing hub provided with a longitudinal slot therein formed above its axis of oscillation and on the side of said axis opposite that of the valve and the cam shaft, an eccentric 35 in the bearing hub free to rotate therein but subject to a clamping action to grip it for oscillation with the rocker arm when the latter responds to the cam shaft to actuate the spring loaded valve thereby causing said hub to contract, and means driven from the cam shaft to 40 adjustably turn the eccentric upwardly away from the valve and cam shaft to loosen up the rocker arm in relation to said valve and cam shaft, and a torque spring coiled about the axis of the eccentric 45 and attached to said eccentric for adjustably turning it downwardly to reset the rocker arm to a no-clearance working relation with the valve and cam shaft.
9. A rocker arm for actuating a spring loaded 50 valve, comprising a bearing hub made of elastic metal and provided with a longitudinal slit therein formed above its axis of oscillation and on the side of said axis opposite that of the valve, an eccentric in the slit bearing hub and free to rotate 55 therein but subject to a clamping action to lock it for oscillation with the rocker arm when the latter actuates the spring loaded valve causing said hub to elastically contract, and means to adjustably turn the eccentric in the bearing hub 60 and thereby compensate the rocker arm to a no-clearance relation with the valve.
10. A rocker arm for actuating a spring loaded valve in relation to its seat, comprising a bearing hub formed in said rocker arm, said hub being 65 formed of elastic or resilient material and cut thru to its bearing to render the latter variable in diameter, an eccentric rotatably free within the elastically variable bearing hub when the latter is at its greater diameter and adapted to 70 be gripped therein against rotation when the hub contracts and reduces its diameter, and independently operable means to adjustably turn the eccentric in both directions in the hub when the latter is expanded to adjust the rocker arm to a 75 no-clearance relation with the valve.
11. A rocker arm and valve operating mechanism, comprising a rocker means adapted to oscillate on a rock shaft and to actuate a valve in relation to its seat, a hub of greater diameter than the rock shaft and having arms integral therewith, said hub being cut thru to form a pinch slot between the arms above the valve, an eccentric confined in the slotted hub and bored to form a bearing on the rock shaft, said eccentric having its major axis disposed perpendicular to the valve, an actuating device to adjust the eccentric upwardly away from the valve when the rocker is not in motion, and a torque spring connected with the eccentric to adjust it downwardly when the rocker arm is not in motion. 80
12. Valve operating mechanism comprising in combination, a pair of rocker arms adapted to oscillate about the same axis on a common shaft, an eccentric bearing on which each rocker arm is mounted, means to lock each eccentric bearing to its rocker arm only when the latter is in motion, sleeve means oscillated on the aforesaid axis and shaft by the rocker arm and engaging one eccentric bearing to turn it in one direction relatively within its rocker arm when the other bearing is locked in and oscillating with its rocker arm, and torque spring means to actuate the bearing in the other direction. 85
13. Valve operating mechanism comprising in combination, a pair of rocker arms adapted to oscillate about a common axis, an eccentric bearing on the same axis and on which each rocker arm is mounted, means effected by movement of the rocker arm to lock the eccentric bearing therein, sleeve means interconnected between each eccentric bearing and oscillated on said common axis by the rocker arm to turn one eccentric bearing in one direction within its rocker arm when the other eccentric bearing is locked in and oscillating with its rocker arm, and torque spring means attached to each bearing to actuate same in the other direction. 90
14. Valve operating mechanism comprising in combination, a pair of rocker arms adapted to oscillate on a common rock shaft, an eccentric bearing on which each rocker arm is mounted, means to lock each bearing in its rocker arm when the latter is in motion, sleeve means oscillated on the same rock shaft by the rocker arm and serving to turn one eccentric bearing in one direction within its rocker arm when the other eccentric bearing is locked in and oscillating with its rocker arm, torque spring means wound axially around the sleeve means between the two rocker arms and secured to each eccentric bearing to adjust said bearing in the other direction, and means anchoring the center of said spring in stationary position. 100
15. Valve operating mechanism comprising in combination, a pair of rocker arms mounted in spaced relation, an eccentric bearing movably free in each rocker arm, a sleeve extension integral with a bearing and reaching toward the other bearing, an operating connection between the sleeve extension and said other bearing by which the movement of one rocker arm actuates the other bearing in one direction, releasable locking means to grip one bearing in its hub when the other bearing is free in its hub, and spring means attached to each bearing to actuate it in the other direction after the locking means has released. 110
16. Valve operating mechanism comprising in combination, a pair of rocker arms mounted in spaced relation, an eccentric bearing movably 115

- free in each rocker arm; a sleeve carried by each bearing, reaching toward the other, and having coacting shoulder means by which one sleeve engages the other; clamping means to grip one bearing in its rocker arm when the other bearing is free in the other rocker arm, and a torque spring means for each bearing coiled around each sleeve and connected to said bearing.
17. Valve operating mechanism as defined in claim 15 but provided with lost motion means at the operation connection between the sleeve extension and said other bearing by which one rocker arm moves part way before actuating the bearing in the other rocker arm.
18. Valve operating mechanism as covered in claim 16, characterized by a lost motion space being provided between the coacting shoulder means, whereby a part only of the motion of one rocker arm is transmitted to the eccentric bearing of the other rocker arm.
19. A rocker arm pair, in combination, for operating valves, and mounted in spaced relation, an eccentric bearing and releasable locking means to alternately fix and release same within each rocker arm, a motion transmitting device interconnected between the two spaced eccentric bearings so that they both turn together in one direction, and spring means tensioned against said eccentric bearings to urge them in the other direction.
20. A rocker arm pair, in combination, for operating valves, and mounted in spaced relation, an eccentric bearing and releasable locking means to alternately fix and release same within each rocker arm, a motion transmitting device interconnected between the two spaced eccentric bearings so that they both turn together in one direction, means affording lost motion in the device whereby one bearing initially starts and turns part way before picking up the other bearing, and spring means tensioned against said eccentric bearings to urge them in the other direction.
21. Valve operating means, comprising two rocker arms, in combination, to actuate valves in respect to their seats, a compensating bearing for each rocker arm, each bearing provided with a hole in its end directed toward the other bearing, two coil springs interposed axially between the bearings and resiliently expanding against the bearings to hold them and the rocker arms in spaced relation, the two springs being integrally joined at their adjacent ends and anchorage means thereat to hold this joined spring in stationary position, said two springs being coiled in the same direction axially in respect to the bearings and having their outer free ends inserted in the hole aforesaid of each bearing and being initially tensioned to exert an adjustable turning force on each bearing in one and the same direction, positively driven means operatively connected with the bearings to turn them in the other and same direction, and locking means to restrain the bearings from movement in respect to the rocker arms during the actuating period of the latter but releasable when the rocker arms are at rest whereby the springs and positively driven means may operate the bearings aforesaid.
22. An assembly for valve operating mechanism, comprising a rocker arm having a bearing receiving hub between its arms, said hub being split lengthwise between its arms to render the hub contractible, an eccentric bearing rotatably confined within the hub and the major axis of said eccentric being disposed substantially parallel to the arms, and a coil torque spring attached to the eccentric bearing.
23. An assembly for valve operating mechanism, comprising a rocker arm having a bearing receiving hub between its arms, said hub being split lengthwise between its arms to render the hub contractible, an eccentric bearing rotatably confined within the hub and the major axis of said eccentric being disposed substantially parallel to the arms, said eccentric bearing being bored to form an internal bearing adapted to receive a rock shaft, a sleeve extension carried by the eccentric bearing and projecting axially from the bore, and a coil torque spring attached to the eccentric bearing.
24. An assembly for valve operating mechanism, comprising a rocker arm having a hub intermediate its ends, said hub being split between its arms at the upper portion of said hub, an eccentric mounted in the hub with the major axis of said eccentric disposed substantially perpendicular to the plane of the split and parallel to the arms, said eccentric being bored to form a bearing adapted to receive a shaft, a sleeve projecting from the eccentric axially of its bore and having engaging means to operatively connect with mechanically driven means, and a torque spring coil wrapped about the sleeve and connected with the eccentric.
25. An assembly for valve operating mechanism, comprising a pair of spaced eccentrics each of which includes a sleeve projecting toward the other and abutting substantially centrally of the eccentrics, each of said abutting sleeve ends made with a clutch means approximately the counterpart of the other and engaged with lost motion by which each eccentric transmits motion to the other in reversely recurring operations, a two-part torque spring having one end coiled around one sleeve and attached to one eccentric and its other end similarly coiled around the other sleeve and attached to the other eccentric, and a rocker arm having a split hub mounted on each eccentric.
26. As an article of manufacture for use in connection with valve operating mechanism, a rocker arm having a bearing receiving hub intermediate its ends, an eccentric snugly fitting in the bearing receiving hub, and said hub being split thru its upper portion to render said hub elastic for contraction to grip the eccentric when an operating force is applied to the arms under the split and for expansion to release the eccentric when the operating force is released.

ROBERT C. RUSSELL.
